GEORGE N. GRAHAM, OF NEW YORK, N. Y.

STEAM-TRAP.

1,074,048.

Specification of Letters Patent. Patented Sept. 23, 1913.

Application filed May 9, 1912. Serial No. 696,252.

To all whom it may concern:

Be it known that I, GEORGE N. GRAHAM, a citizen of the United States, residing at New York, in the county of New York and State of New York, have invented certain new and useful Improvements in Steam-Traps, of which the following is a specification.

This invention relates to steam traps, and 10 belongs to the class of such devices each of which includes, among other parts, a weight-carrying member and float-operated means constructed and arranged to actuate the weight-carrying member in such manner 15 that the weight is alternately thrown on opposite sides of the perpendicular, for the purpose of quickly opening and quickly closing an operatively connected valve, to prevent wire-drawing of the steam and water, 20 and to insure the positive, full opening and closing of the valve each time the weight is thrown.

The object of this invention is the production of a steam trap comprising parts of 25 special construction and arrangement whereby it is believed the certainty, completeness and promptness of operation are materially increased under ordinary working conditions, beyond what is met with in apparatus 30 for like purpose commonly employed.

The preferred construction of this invention is illustrated in the accompanying drawings, of which—

Figure 1 represents a vertical section 35 lengthwise of the casing, all parts being assembled. Fig. 2 is an end view, the dished member of the casing having been removed to disclose internal parts. Fig. 3 is a vertical cross-section, somewhat enlarged, showing the movable seat for the float, and the toggle or knuckle joints connected therewith. Fig. 4 is a like section to Fig. 3 taken on a plane at right angles to the plane of that section. Fig. 5 is a vertical section of the 40 lower end of the dished member of the casing, and Fig. 6 is an inside view of the same end of that member, both views showing the pocket bearings for the rocking shaft. Fig. 7 is a view of the valve seat cup detached, 45 and looking into the open end thereof. Fig. 8 is a horizontal section, somewhat enlarged, of the valve rod bracket, showing also in section the valve seat cup and the cage to which those parts are attached. Fig. 9 shows the right hand end of the cage as 50 illustrated in Fig. 8. Fig. 10 is a cross-

section of the removable cage. The section shown in Fig. 1 is taken on the indirect line 1—1 of Fig. 2. The section shown in Fig. 4 is taken on broken line 2—2 of Fig. 3. The 60 section of the detached parts shown in Fig. 8 is taken on line α — α of Fig. 1, and the cross-section shown in Fig. 10 is taken on line 3—3 of Fig. 8.

In the description and throughout the 65 drawings, the same character is used to refer to the same part.

Considering the drawings, the main portion of the casing is marked A. It has a complementary dished portion a which is 70 removable. The casing A has an internally projecting part B, and a base b. The interiorly projecting part B is hollow, forming a chamber D, having an open end closed by a removable head d. The head is clamped 75 in place by the nut E on the removable stem e threaded as shown in Fig. 1 to engage the nut. The stem e is removably attached to a cage F, having openings f into the chamber D. The outlets G and g lead from the chamber D, as illustrated in Figs. 1 and 2. The valve seat cup H, having the valve seat h, is threaded into the base of the cage at one side of the center, as best shown in Figs. 2 and 8. The needle valve J occupies the seat, 80 and, a fin collar or feathered sleeve j is placed on valve rod K near the valve J to support and guide the rod in the hollow of cup H. The other or outer end of rod K is supported by the bracket k attached to the 85 base of cage F and removable with the cage.

Upon the valve rod K are two fixed collars l and l, between which are arranged the lugs M forming part of the longer member N of a knuckle joint, of which the upper 95 and shorter member is marked n. The knuckle member n is pivotally secured to the float seat pan O, to which is also pivotally secured the smaller member p of a second knuckle joint similar to that already mentioned and of which the longer member is marked P. A shaft Q, transversely arranged with respect to the valve rod K, and a short distance above it, as best shown in Figs. 3 and 4, is provided with a squared 100 portion R, to be again referred to. More fully explained, considering Figs. 3 and 4, the knuckle or toggle joint comprises the single arm N engaging the squared portion R of the shaft Q, and, therefore, compelled 105 to move with the shaft, and the two short arms or links n arranged to connect the sin-

gle arm *N* pivotally with the lugs of the float seat or pan *O*. The remaining parts of the toggle joint comprise the arms *P* having the same length as the arm *N*, but movably engaging the cylindrical end portions of the shaft *Q*. The arms *P* are pivotally connected at their upper ends with the float seat by the link *p* of the same length and construction as the members or links *n* already mentioned.

10 Pocket bearings *S* and *s*, as best illustrated in Figs. 5 and 6 are formed at the sides of the interior of the dished member *a* of the casing of this invention. It is thought 15 to be apparent that the shaft may be lifted from the bearings when the member *a* of the casing is taken off.

The float element of this invention shown is marked *T* and is arranged above the seat 20 pan *O*, upon which it may rest as illustrated in Figs. 1 and 2. The float is provided with a stem *t* extending downwardly and passing through a central orifice *U* in pan *O*, and having the terminal nut *u* on its lower end.

25 The remaining parts of this invention are best described in connection with the explanation of the mode of its operation. It will be observed in Fig. 4 that the member *N* of the knuckle joint first mentioned herein has its hub located at the middle of the squared portion *R* of shaft *Q*, and that the C-shaped rod *V*, has a fork *v* at its lower end the prongs of which engage the squared portion *R* on both sides of the hub of the member *N*. The members *P* of the second knuckle joint are in pivotal connection with the round portion of shaft *Q*, therefore, as the float rises the toggle joint is elongated, the shaft *Q* is turned, and, by reason of the attachment of the fork *v* to the shaft as shown in Figs. 2, 3, and 4, the rod *V* is actuated correspondingly. The float may rise from its position in Fig. 1, as the casing fills with water of condensation, for a little distance 40 and until the nut *u* on the lower end of stem *t* of the float encounters the bottom of pan *O*. Thereafter, further rising of float *T* draws on the member *N*, turning shaft *Q* and moving the C-shaped rod *V* until the weight *W* on the upper and threaded end *w* of rod *V*, passes over the perpendicular and falls into the position indicated by the broken lines. The lugs *M* are thrown abruptly against fixed collar *L* on rod *K* and 45 the valve is instantly and fully opened in the usual way. The falling float, as the casing is discharged, soon rests its weight on pan *O* and causes a reversal of the movement of the weight and rod, restoring them 50 to the positions shown in Fig. 1.

The weight is adjustably secured on the threaded end *w* of rod *V* by means of the nuts *Y* and *y*. It will be noted that the body of the rod *V* is vertical, and that the 55 portion *w* thereof is horizontal and is ar-

ranged to move above the float. The weight *W* is adjustably secured upon the horizontal portion of the rod and during the operation moves back and forth across a perpendicular passing through the float. During 70 the operation, the shaft *Q* is retained in the pocket bearings *S* and *s* for the reason that the openings of those bearings rest against suitable lugs 4 and 5 on the interior of the main portion *A* of the casing.

75 It is believed to be an advantageous feature of this invention, that the internal parts may be easily removed for shipment or repairs. For example, upon the removal of the dished member *a* of the casing, the weight and its rod, together with the float, pan *O*, knuckle joints and shaft *Q* may be lifted out as one piece and replaced likewise. By removing nut *E*, head *d* may be detached, and the valve seat *h* becomes accessible through openings *f* of cage *F*. If desired, the cage, valve, valve rod and bracket *k* may all be drawn out through chamber *D* as one piece, by turning the cage on its axis contrary to watch hands, thereby disengaging spiral groove *6* in the surface of the cage, and pin *7* in base *b*, as shown in Fig. 1. It will be noted that the action of screwing up nut *E* on stem *e* to clamp head *d*, so far as such action exerts any turning effect upon the stem *e*, tends to turn the stem and cage *F* with the hands of a watch, and to tighten the engagement of the spiral groove *6* and pin *7*.

Having now described this invention, and 100 explained the mode of its operation, what I claim is:—

1. In a steam trap, the combination with a casing comprising a main portion having an interiorly-projecting portion and a base, the said projecting portion and base being constructed and arranged to form a chamber between them, the said chamber having discharge outlets and an open end, of a head constructed to close the end of the 105 chamber, a cage having a stem passing outwardly through said head, means acting upon the stem and constructed to clamp the said head upon the open end of the chamber, the inner wall of said chamber being 110 apertured to receive the end of said cage, means constructed to removably secure said end of the cage, the cage being removable through said chamber, a device having a valve seat, the said end of the cage being 115 apertured to receive and engage said device, a valve and valve rod movably supported upon the cage and removable therewith, and float-operated means constructed and arranged to actuate the valve rod.

2. In a steam trap, the combination with a casing comprising a main portion having an interiorly-projecting portion and a base, the said projecting portion and base being constructed and arranged to form a cham- 120

ber between them, the said chamber having discharge outlets and an open end, of a head constructed to close the open end of the chamber, a cage having a stem passing outwardly through said head, means acting upon the stem and constructed to clamp the said head upon the open end of said chamber, the inner wall of said chamber being apertured to receive the end of the 5 cage, means constructed to removably secure the said end of the cage, the said cage being removable through said chamber, the said cage being provided with a valve seat, a movably supported valve arranged to engage said seat, and float-operated means 10 constructed and arranged to actuate the valve.

3. In a steam trap, the combination with a casing comprising a main portion and a removable portion having interiorly-projecting pocket bearings, said pocket bearings having openings presented toward the main portion of the casing, a shaft having 15 ends supported in said bearings, the said 20 main portion of the casing being construct-

ed to obstruct the said openings of the pocket bearings and to retain said shaft therein, said casing having a valve seat, a valve movably supported and arranged to engage said seat, and float-operated means 30 connected with said shaft and constructed and arranged to actuate said valve.

4. The combination with a valve and valve-operating devices, of a float movably connected with said devices and constructed to actuate them, a rod attached to said valve-operating devices and having a vertical portion and a horizontal portion arranged to move above said float, and a weight adjustably secured upon the horizontal portion of the rod and arranged to be moved by the rod back and forth across a perpendicular passing through the float. 35

In testimony whereof I affix my signature in presence of two witnesses.

GEORGE N. GRAHAM.
